HANDLE FOR MATTRESSES

Peter C. Bednarek, Chicago, Ill., assignor to
Ostermoor & Company, Bridgeport, Conn., a
corporation of New York

Application June 21, 1941, Serial No. 399,079

2 Claims. (CL. 5—345)

The invention relates to handles for mattresses.

One object of the invention is to provide a handle for a mattress which comprises a woven or braided flat strip forming a grip which, when not in use, will fit closely against the outer face of the box-border of the mattress, which can be secured to the box-border by simple securing means, and which is durable.

Other objects of the invention will appear from the detailed description.

The invention consists in the several novel features which are hereinafter set forth and are more particularly defined by claims at the conclusion hereof.

In the drawing: Fig. 1 is a perspective of a portion of a mattress embodying the invention. Fig. 2 is a horizontal section through the box-border and the devices for securing the ends of the handle-strip thereto. Fig. 3 is a perspective of one of the eyelets. Fig. 4 is a perspective of one of the plates which are adapted to be clamped against the inner face of the box-border. Fig. 5 is a perspective of one of the clips for securing the end of the handle-strip against withdrawal through the eyelets. Fig. 6 is a perspective of a portion of the handle-strip. Fig. 7 is a horizontal section through one of the eyelets illustrating the manner of assembling the eyelet and plate with the box-border.

The invention is exemplified in a mattress *a* which may be of any suitable construction and is provided with the usual box-border *b*. A tape-like stout woven or braided strip *10* forms a grip which is adapted to lie flatwise against the outer face of the box-border. Said strip has its ends extended through a pair of eyelets to the inner side of the border and secured therein so as to prevent the withdrawal of the ends from the eyelets when the handle is used in lifting the mattress. Each eyelet comprises a transverse flange *11* with vertically straight sides *12* connected by rounded upper and lower ends *13* which form a vertically elongated opening *14* which conforms substantially to the cross-sectional contour of the strip *10* so that the strip will be held against curling or folding by the flanges around the openings when subjected to tension or while being gripped by a hand. Each eyelet also comprises an out-turned flange *16* conforming in contour to the opening *14* and fitting against the outer face of the box-border. A plate *17* has a vertically elongated opening *18* which fits snugly around the transverse flange *12* and is adapted to engage the inner face of the box-border. Each eyelet is also provided with an out-turned flange

19 which overlaps the inner face of plate *17* and is pressed against said plate so that the box-border will be tightly clamped between the plate and the front flange *16* of the eyelet. In assembling the eyelets and the box-border the plates *17* are slipped onto the transverse flanges *11* before the flanges *19* are formed thereon, as illustrated in Fig. 7. The inner ends of the transverse flange are next bent outwardly and pressed against plate *17*. Flange *19* is subjected to pressure to cause the border to be securely clamped between flanges *16* and plates *17*. The plates *17*, which are subjected to the load in lifting, are preferably of greater area than the flanges *16* to distribute the pressure of plates *17* over a greater area of the inner face of the border. After the eyelets have been secured in the box-border the ends of strip *10* are passed through the eyelets. The inner terminals of the strip are reverted or doubled over, as at *20*, to provide an enlargement on the inner ends of strip *10*. Clasps *21* formed of flat metal and provided with teeth *22* along their vertical edges, are then folded around the reverted ends *20* and the teeth *22* are pressed together so they will penetrate the strip and be rigidly secured thereto. When the clasps are secured on the strip *10* the reverted ends and clasps will prevent the inner ends of strip *10* from being withdrawn through the eyelets. The clasp *22* also functions to prevent any warping or curling of the fabric so that it will remain flat at all times. The eyelets with the elongated openings also serve to keep the strip *10* flat when under load.

The invention exemplifies a device in which a relatively wide flexible stout flat strip forms a grip by which the mattress can be readily handled and which has its ends secured in the box-border so it will remain flat during use and which has its inner ends securely held against withdrawal from the eyelets.

The invention is not to be understood as restricted to the details set forth, since these may be modified within the scope of the appended claims, without departing from the spirit and scope of the invention.

Having thus described the invention, what I claim as new and desire to secure by Letters Patent is:

1. The combination with the box-border of a mattress of a pair of eyelets, each eyelet comprising a transverse flange extending through an opening in the border and having vertically elongated straight sides and rounded upper and lower ends forming a vertically elongated straight-

sided opening through the border and an out-turned flange fitting against the outer face of the border, plates fitting around the outside of the transverse flange, each plate having an opening conforming to one of the transverse flanges and fitting against the inner face of the border, an out-turned integral flange on the inner end of each transverse flange fitting against the inner face of one of the plates and clamping the border between one of the outside flanges and one of the plates, a strip of flat flexible fabric extending across the outside of the border, forming a grip, extended through and conforming in cross-section to the contour of the elongated openings in the eyelets and having ends on the inner side of the eyelets and box-border formed into rolls which form enlargements, and clips of flat metal cylindrically folded and permanently clenched around the rolls, respectively, the clips and rolls forming means for preventing withdrawal of the ends of the strip from the eyelets, the flexible strip having terminals extended to lie between one side of the clips and the inner face of the eyelets.

2. The combination with the box-border of a mattress of a pair of eyelets, each eyelet comprising a transverse flange extending through an opening in the border and having vertically

elongated straight sides and upper and lower ends forming a vertically elongated straight-sided opening through the border and an out-turned flange fitting against the outer face of the border, plates fitting around the outside of the transverse flange, each plate having an opening conforming to one of the transverse flanges and fitting against the inner face of the border, an out-turned integral flange on the inner end of each transverse flange fitting against the inner face of one of the plates and clamping the border between one of the outside flanges and one of the plates, a strip of flat flexible fabric extending across the outside of the border, forming a grip, and extended through and conforming in cross-section to the contour of the elongated openings in the eyelets, and having ends on the inner side of the eyelets and the box-border formed into rolls which form enlargements, and clips of flat metal cylindrically folded around the rolls and having teeth permanently clenched into the strip, the clips and rolls forming means for preventing withdrawal of the ends of the flexible strip from the eyelets, the flexible strip having terminals extended to lie between one side of the clips and the inner face of the eyelets.

PETER C. BEDNAREK.
